SUPPORT STRUCTURE

This application is a continuation-in-part application of my copending U.S. application Ser. No. 558,142, filed June 16, 1966 and now U.S. Pat. No. 3,490,886 dated Nov. 25, 1969 and the full and complete disclosure thereof is hereby expressively incorporated, by reference, into and forms a part of the present application. His invention relates to novel and improved support means and, more particularly to novel and improved means for supporting articles and furnishing heat thereto while retaining accurate center-to-center distances therebetween.

In my copending application Ser. No. 558,142, there is disclosed methods, apparatus and systems for assembling and sealing devices having generally tubular casing members, such as glass enclosed semiconductor diodes. A lower assembly is disclosed therein having a plurality of chucking portions for supporting a plurality of such generally tubular casings with an open end thereof disposed generally upwardly and with the axes thereof being generally parallel and in line. Further, provision is disclosed for applying heat to the lower assembly for enabling process heating, such as soldering, of the device being fabricated during, or substantially simultaneously, with the sealing operation. However, the lower assembly as disclosed in the aforesaid copending application has been found to be of less than optimum design since dimensional changes are introduced to lower assembly during such heating which may result in misalignment between the upper and lower assemblies.

Accordingly, it is a primary object of the present invention, in addition to the objects and important features set forth in the above-identified copending application, to provide apparatus of the class described which is substantially insensitive to temperature changes and wherein center-to-center distances are maintained even during severe temperature changes.

Another primary object of the present invention, in addition to the foregoing objects, is the provision of a novel and improved lower assembly for utilization with equipment of the class described.

Still another primary object of the present invention, in addition to each of the foregoing objects, is the provision of such a lower assembly wherein each chucking unit is substantially independent of the adjacent chucking unit and are each mounted on a substantially thermally insensitive amount fabricated, for example, of a ceramic material.

Yet still further, it is another primary object of the present invention, in addition to each of the foregoing objects, to provide such chucking means with means for adding heat thereto so that control process heating of the article gripped thereby may be performed yet without affecting the center-to-center distance between adjacent chucking units.

Yet further, it is still another primary object of the present invention, in addition to each of the foregoing objects, to provide such a lower assembly which is economical to manufacture and durable and efficient in use.

The invention resides in the combination, construction, arrangement and disposition of the various component parts and elements incorporated in improved apparatus constructed in accordance with the principles of this invention. The present invention will be better understood and objects and important features other than those specifically enumerated above will become apparent when consideration is given to the following details and description, which when taken in conjunction with the annexed drawing describes, discloses, illustrates and shows a preferred embodiment or modification of the present invention and what is presently considered and believed to be the best mode of practicing the principles thereof. Other embodiments or modifications may be suggested to those having the benefit of the teachings herein, and such other embodiments or modifications are intended to be reserved especially as they fall within the scope and spirit of the subjoined claims.

In the drawing:

FIG. 1 is a side elevational, cross-sectional, partial view of sealing apparatus incorporating a lower assembly constructed in accordance with the present invention and

FIG. 2 is a front elevational, cross-sectional, partial view taken along line 2—2 of FIG. 1.

FIGS. 1 and 2 are substantially similar to FIGS. 6 and 7 of the aforesaid copending parent application but illustrating the improved lower assembly of the present application.

With reference now to the drawing, there is shown and illustrated a sealing machine substantially similar to the sealing machine fully described and disclosed in the aforesaid copending parent application. In the interest of brevity, therefore, the sealing machine will not be herein described in detail, reference being had instead to the aforesaid copending parent application, the complete disclosure of which is expressly incorporated herein and forms a part of this application. Like reference characters will be used in this application as in the aforesaid copending parent application, with the exception that those parts of the lower assembly which differ in the present application from those of the aforesaid copending parent application will be primed. Further description of the component parts and elements of the sealing machine, designated by the reference character 60', is therefore not deemed necessary herein, except to point out that the sealing machine 60' may comprise a base structure 68 for supporting lower clamping or chucking assemblies 44' and a bell jar 70 structurally associated with a movable upper chucking assembly 26 and movable relative to the base block assembly 68 between an open loading position and a closed seal position, as shown, wherein an O-ring gasket 72 provides a seal therebetween to define a hermetically sealed sealing chamber 15 therebetween. A plurality of chucking sections or stations 86' may be provided in generally aligned relationship.

The lower clamping or chucking assembly 44' may comprise a fixed jaw 46' at each of the chucking stations 86', each fixed jaw 46' being provided with a gripping portion 48 constructed and arranged to grip a tubular casing member of a device to be sealed and a support surface or portion 50 for the annular end portion of the tubular casing member. Each of the fixed jaws 46' may further be provided with a generally vertically extending aperture 52 to enable passage therethrough of a lower lead wire extending deownwardly axially of the casing member.

A movable jaw 54, having a casing gripping portion 56 is provided for actuation to move into gripping heat transfer engagement with such casing member adjacent the fixed jaw 46' as fully detailed in the aforesaid copending parent application.

Each of the fixed jaws 46', which may be fabricated, for example, of a highly thermally conductive material, such as copper, or the like, may be separately mounted, as by means of screws 302, to an elongated support 304 fabricated of a material which is substantially thermally insensitive, such as a ceramic, or the like, so that it will not change its dimensions upon heating and cooling by any substantial degree. The support 304, in turn, may be mounted with the base block, as by means of screws 306 extending generally downwardly therethrough. Accordingly, since each of the fixed jaws 46' are separated from the adjacent fixed jaws, as by a space 306 therebetween, and are mounted to a substantially thermally insensitive material, or a material having a low coefficient of thermal expansion the center-to-center distance between the stations 86' will not be affected, to any substantial degree, by temperature changes.

The rear surface of each of the fixed jaws 46' may be provided with a generally transversely extending groove 308, through which a heater element 134' comprising, for example, an electrical resistance wire contained within a ceramic sheath, may extend for heating the fixed jaws 46' and, therefore, the lower end portion of the device or devices supported thereby.

The heater assemblies 58 and the connector blocks 142 and 143 associated therewith may similarly be secured, as by means of screws 133 on an insulator 132 disposed generally on top of the block 304 and secured, as by means of the screws 306 so that the center-to-center distances therebetween may be maintained.

The entire lower assembly is, as in the aforesaid copending parent application readily and easily removable from the lower block for rapid and easy adaptation of the machine to various diverse packages.

While the invention has been described, disclosed, illustrated and shown in terms of certain embodiments or modifications which it has assumed in practice, the scope of the invention should not be deemed to be limited by the precise embodiments or modifications herein described, disclosed, illustrated or shown, such other embodiments or modifications as may be suggested to those having the benefit of the teachings herein being intended to be reserved especially as they fall within the scope and breadth of the claims here appended.

What is claimed is:

1. Assembly for supporting a plurality of casing members generally upright within a chamber for heat sealing thereof comprising, in combination, a plurality of separated fixed chuck elements disposed in said chamber in general alignment with each other generally longitudinally through said chamber to define a plurality of sealing stations and an elongated support fabricated of a material having a low thermal coefficient of expansion extending generally across the chamber generally adjacent each of said sealing stations, each of said fixed chuck elements being mounted with and supported by said elongated support in spaced-apart relationship to each other, the coefficient of expansion of the material of said elongated support being so chosen that upon a change of temperature of said chuck elements the center-to-center spacing therebetween remains substantially constant.

2. Assembly defined in claim 1 wherein said elongated support further comprises a thermally insulating, refractory material so that the temperature thereof will remain substantially constant even during cyclic heating of said fixed chuck elements.

3. Assembly defined in claim 2 wherein said fixed chuck elements are each provided with a groove extending generally transversely thereacross adjacent said elongated support and wherein there is further provided a heating element extending generally through said grooves and between said chuck elements and said elongated support.

4. Assembly defined in claim 3 wherein said fixed chuck ele-

ments comprise a highly thermally conductive material for rapidly transmitting heat from said heating element.

5. Assembly defined in claim 4 further comprising individually mounted movable chuck elements disposed generally oppositely said fixed chuck elements for gripping such casing members therebetween.

6. Assembly defined in claim 5 further comprising sealing heater elements mounted with said elongated support generally above said fixed chuck element for encircling such casing members and supply heat generally annularly thereto.

7. In a machine for assembling and heat sealing a plurality of electronic devices such as glass-enclosed diodes simultaneously within a chamber wherein accurate positioning of each such device within said chamber is necessary for successful assembling and sealing, an assembly within said chamber supporting a plurality of casing members for such devices generally upright therewithin and comprising, in combination, an elongated support fabricated of a material having a low thermal coefficient of expansion extending generally across

20 said chamber, a plurality of adjacent spaced-apart chucking elements independently mounted with said elongated support the coefficient of expansion of the material of said elongated support being chosen so that no dimensional changes occurs in said chucking elements due to temperature changes and

25 variations during or due to heat sealing cycling which cause stress to occur in said adjacent chucking elements or which cause any cumulative effect across the plurality of chucking elements, thereby enabling center-to-center spacing therebetween to reaming substantially constant and independent of the temperatures thereof.

8. Machine defined in claim 7 wherein said elongated support further comprises a thermally insulating, refractory material so that the temperature thereof will remain substantially constant even during cyclic heating of said chucking elements to thereby further reduce center-to-center spacing variations during cyclic operations.

9. Machine defined in claim 8 wherein said chucking elements are fabricated of a material having high thermal diffusivity and further comprising heating means associated with 40 said chucking elements for providing heat thereto.

10. Machine defined in claim 9 wherein said chucking elements comprise cooperating pairs of fixed and movable jaws and wherein each of said fixed jaws is provided with a groove extending generally transversely thereacross adjacent said elongated support and said heating means comprises a heating element extending generally through said grooves.
